Primary Examiner—Lucy J. Lieberman*Attorney, Agent, or Firm*—Baxley, Charles E.[57] **CLAIM**

The ornamental design for a bottle, as shown and described.

DESCRIPTION

FIG. 1 is a front elevational view of a bottle according to my design, the rear elevational view being a mirror image of FIG. 1;

FIG. 2 is a right side elevational view thereof, the left side elevational view thereof being a mirror image of FIG. 2; and,

FIG. 3 is a top plan view thereof.

The bottom of the bottle is flat and unornamented.

FIG. 1.

FIG. 2.

FIG. 3.
